Mason Fenwick Lawrence

ATTORNEYS

UNITED STATES PATENT OFFICE.

HOMER LEWIS OSBORN, OF NEW YORK, N. Y.

VALET CHAIR.

Application filed August 25, 1923. Serial No. 659,374.

To all whom it may concern:

Be it known that I, HOMER LEWIS OSBORN, a citizen of United States, residing at New York, in the county of New York and State of New York, have invented certain new and useful Improvements in Valet Chairs; and I do hereby declare the following to be a full, clear, and exact description of the invention, such as will enable others skilled in the art to which it appertains to make and use the same.

This invention relates to garment hangers and more particularly to hangers associated with an article of furniture, such as a chair. The objects of the invention are to provide a garment hanger which will combine with the configuration of the chair so as not to be noticeable when out of use and yet may be conveniently brought into use when desired; to permit the chair to be utilized as a part of the garment hanger; to provide a garment hanger which will support both trousers and a coat; to provide that the trousers may be conveniently applied to the garment hanger either before or after the coat is hung on the chair; to provide trouser hangers which disappear when folded, so as to be out of the way and out of sight; to utilize the trouser hanger as a spring for ejecting the same from the pocket in the chair when desired to use said trouser hanger; to secure simplicity of construction and operation and to obtain other advantages and results as may be brought out in the following description.

Referring to the accompanying drawing in which like numerals of reference indicate similar parts throughout the several views:

Figure 1 is a rear view of a chair embodying my invention showing the trouser hanger closed;

Figure 2 is a similar view showing the trouser hanger in operative position and in use;

Figures 3 and 4 are sectional views on lines 3—3 and 4—4 of Figs. 1 and 2 respectively, and

Figure 5 is an enlarged detail view of a catch employed on the trouser hanger panel.

In the specific embodiment of the invention illustrated in said drawing, the reference numeral 1 indicates in general a chair having back 2 the upper end 3 of which is of such a configuration as to conveniently and properly support a coat when

hung over the same. From the center of the top of said back is provided an extension 4. The extension is preferably employed so as to provide a means for mounting the pants above the position assumed by a coat hanging upon the coat hanger portion 3 of the chair. It will be observed that the extension 4 is preferably of a configuration to harmonize with the general structure or configuration of the chair and would ordinarily be a part of the design of the chair and not merely an extension for the particular purpose of supporting the trouser hanger. However, I wish to state at this time that I do not confine myself to the use of this particular style extension, nor to any extension at all if found more desirable to support the trouser in some other place to the chair.

In the back of the chair and preferably in the back of the extension 4 of the chair disclosed in the drawing, I provide a pocket 5 adapted to open toward the rear of the chair and closed toward the front so as not to detract from the appearance of the chair from the front nor to be otherwise objectionable. This pocket 5 is preferably provided with a panel 6 for closing the same as shown in the drawing, said panel being arranged to swing horizontally by virtue of a vertically disposed hinge 7 at one end of the panel and pocket. By use of this panel, the pocket or opening may be closed and thus obtain a neat appearance of the chair when the trouser hanger is not being used. In order to hold the panel closed, I preferably provide a spring operated catch 8 shown in Figure 5 as imbedded in the panel 6 and operable by means of a finger piece 9.

In the preferred construction I mount trouser hanger 10 upon panel 6, and arrange the same so that when the panel is closed the trouser hanger 10 is within the pocket 5, and when the panel 6 is opened the trouser hanger is arranged at the rear of the chair in a convenient position for use. Obviously any suitable type of trouser hanger may be employed in connection with the pocket 5 and panel 6, and for purpose of illustration a wire trouser hanger is shown providing tines arranged close enough together for trousers to be slipped in between and frictionally gripped thereby. These tines are resilient, and this qualification is utilized both for supporting the trousers

and providing means for opening the panel when the catch is drawn back. In other words, the trouser hanger is compressed upon closing the panel and this will operate 5 to cause the panel to swing outwardly upon releasing catch 8.

In use, the chair may be employed as usual and the fact that it may also be employed as a garment support is not particularly noticeable or objectionable. When it 10 is desired to hang garments upon the chair the party may hang his coat either before or after opening panel 6 and before or after hanging his trousers upon the trouser 15 hanger 10. The trouser hanger is permanently affixed to the chair so that it will always be ready for use.

Obviously detail changes and modifications may be made in the manufacture and 20 use of my improved garment hanger, without departing from the spirit or scope of the invention.

Having thus described my invention, I 25 claim:

1. In combination with a chair back having a pocket, a panel hinged to the chair adapted to close said pocket, a resilient

trouser hanger mounted on said panel and adapted to be compressed within the pocket when the panel is closed so as to actuate the 30 panel outwardly when released.

2. In combination with a chair back having a pocket, a panel hinged to the chair adapted to close said pocket, a resilient trouser hanger mounted on said panel and 35 adapted to be compressed within the pocket when the panel is closed so as to actuate the panel outwardly when released, and a spring catch for retaining the panel in 40 closed position.

3. In combination with a chair back having a pocket, a panel hinged to the chair adapted to close said pocket, a resilient trousers hanger mounted on said panel and 45 adapted to be compressed within the pocket when the panel is closed so as to actuate the panel outwardly when released, said chair back being conformed to the shape of the shoulders and adapted to support a coat 50 thereon.

In testimony whereof I affix my signature.

HOMER LEWIS OSBORN.
